UNITED STATES PATENT OFFICE

2,667,401

CONVERTIBLE CABINET

Harvey G. Knuth, Elgin, Ill., assignor to Lyon Metal Products, Incorporated, Aurora, Ill., a corporation of Illinois

Application November 23, 1945, Serial No. 630,289

10 Claims. (Cl. 312—351)

1

This invention relates to a convertible cabinet or utility cabinet. In the manufacture and use of cabinets the conventional practice is for the manufacturer or vendor to stock different types of cabinets such as broom cabinets, wardrobe cabinets, and the like, all as separate cabinets. This practice requires a large inventory and is space consuming.

Among the objects of the present invention is to provide a convertible cabinet comprising a main cabinet structure provided with spaced apart fastening means substantially coextensive with the height of the cabinet, which fastening devices are adapted to receive and hold various types of auxiliaries, such as shelves, hook racks and the like, wherein by providing a single cabinet of such construction together with a selected number of such auxiliaries, any type of cabinet may be made up from a desired combination of the auxiliaries applied quickly to the main cabinet and detachably fastened into position.

Yet another object of the invention resides in providing details of construction of a sheet metal cabinet which is made of few parts, simple in construction, rigid, and convertible with minimum of effort into a number of different types of cabinets for the storage of different commodities.

Another object of the invention is to provide as subcombination inventions different types of attachments adapted detachably to be fastened in position in the main cabinet, whereby it may be converted as hereinbefore described.

These and other objects of the invention will be apparent from a perusal of the following specification when taken in connection with the accompanying drawing, wherein:

Figure 1 is a perspective front view of the cabinet with the doors closed, showing the cabinet as provided at its upper portion with two spaced apart horizontal shelves, the remainder of the cabinet being free for storage of relatively lengthy articles;

Figure 2 shows a cabinet with the doors removed, purely for purposes of disclosure, and wherein a hook rack has been added so that the cabinet may be used as a cleaning implement cabinet;

Figure 3 shows the cabinet arranged for shelving only, to be used as a shelving type cabinet;

Figure 4 shows the cabinet converted to uses such as a pot and pan cabinet;

Figure 5 is a section taken on the line 5—5 of Figure 1;

Figure 6 is a plan section taken on the line 6—6 of Figure 5;

2

Figure 7 is a fragmentary sectional perspective view, the lower portion of one side of the cabinet and the door being removed;

Figure 8 is an exploded perspective view of the cabinet, showing the relative parts in associated position with respect to each other, the doors not being included;

Figure 9 is a front perspective view of the cabinet without the doors, showing the associated parts as viewed in Figure 8 assembled into position;

Figure 10 is a fragmentary perspective view of the inside of one of the corners of the cabinet construction;

Figure 11 is a perspective view of one of the shelves;

Figure 12 is a fragmentary sectional view of the locking means for the shelves in the cabinet, being taken on the line 12—12 of Figure 13;

Figure 13 is a partial plan section taken on the line 13—13 of Figure 14;

Figure 14 is a central vertical section taken on the line 14—14 of Figure 3;

Figure 15 is a partial plan sectional view taken on the line 15—15 of Figure 16;

Figure 16 is a vertical sectional view of the lower portion of the cabinet and being taken on the line 16—16 of Figure 4;

Figure 17 is a perspective view of the frame mechanism which forms a support for the vertical partitions as shown in Figure 4;

Figure 18 is a perspective view of the two shelves that form partitions in the lower part of the cabinet, as shown in Figure 4;

Figure 19 is a perspective view of the bottom base plate to be used in connection with the construction as shown in Figure 4;

Figure 20 is a detail sectional view taken on the line 20—20 of Figure 19;

Figure 21 is a perspective view of the frame supporting unit as would be used in connection with the type or arrangement of cabinet as shown in Figure 2;

Figure 22 is a detail perspective view of the corner construction of the frame member as shown in Figure 21;

Figure 23 is a vertical sectional view taken on the line 23—23 of Figure 2;

Figure 24 is a fragmentary detail plan sectional view taken on the line 24—24 of Figure 21;

Figure 25 is a perspective view of a modified type of frame construction as adapted to be used in the construction of a cabinet as shown in Figure 4;

Figure 26 is a detail perspective view of one

corner of the frame structure as shown in Figure 25;

Figure 27 is a detail sectional view taken on the line 27—27 of Figure 4;

Figure 28 is a perspective view of one of the supporting hooks to be used in connection with the frame member as shown in Figure 25; and

Figure 29 is a detail perspective view showing the corner construction of the frame as shown in Figure 25.

Referring now to the drawings in detail, the cabinet comprises a built up base support which, as shown in Figure 8, comprises four integral pieces. First there are two channel-shaped sheet metal pieces, the first having the front face 2 and the two right angle flanges 4 and 6. This member constitutes the front base support and is identical with a back base support comprising the vertical face 8 and the two horizontal right angle flanges 10 and 12. Then there are the two side base supports preferably formed of a single piece of sheet metal. The one to the left comprises a vertical face 14 and right angularly extended flanges such as the two opposite end flanges 16 and 18 and the two side flanges 20 and 22. In turn, the side flange 20 has the two depressed portions 24 and 26, while the opposite side flange 22 has the raised portions 28 and 30. The other side base support comprises the plane vertical surface 34 and the end flanges 36, the opposite end flange not being shown, and opposed side flanges. The side flange 38 is provided with the depressed portions 37 and 38 corresponding with the depressed portions 24 and 26 of the opposite side piece and the other side flange is likewise provided with raised portions corresponding to 28 and 30 of the opposite portion. These front and back and side base supports are suitably welded together in the manner shown best in Figure 7 wherein the raised portion 29 of the bottom side flange 22 overlies the basal flange 10 of the back piece 8, being welded thereto, and the raised flange 28 in similar manner overlies and is welded to the basal flange 6 of the front piece 2. In a similar manner the side pieces 24, 26, 36 and 38 are likewise welded in position to the upper flanges 4 and 12 of the front and back pieces 2 and 8. Thus there is provided a very solid base support upon which is bolted the bottom which preferably comprises a single piece of sheet metal such as 40 having integral downwardly extending flanges 42 having an inwardly extending flange 44, the skirt 46 having an inwardly extending flange 48, the rear skirt 50 having an inwardly extending flange 52, and the skirt 54 having an inwardly extending flange 56. These flanges are all welded together at the corners to produce the rigid flanged rectangular bottom piece to receive the bolts which pass through the inwardly turned flanges and the horizontal upper flanges 4 and 12 of the front and back supports, as well as the flanges of the side supports.

In addition, the cabinet comprises two identical side members, the right side member and the left side member. As shown in Figures 7 and 8, the left side member comprises the sheet metal side 58 having a right angularly extending flange 60 which has still another right angularly extending flange 62 terminating in a third flange 64, see Figure 7, whereby to form a substantially hollow, rectangularly extending, upright post. The bottom part of this post is cut out as at 66 and 68, see Figure 7, to fittingly overlie a corner portion of the bottom 40. The front flange 60 is

welded as at 70 to the flange 42 of this bottom and likewise may have the bottom portion of the side 58 welded to the vertical wall 46 at the corner of the bottom. At the rear the side 58 is provided with the right angularly extending flange 70 which extends vertically thereof. The right side of the cabinet is identical with the left. It comprises a side sheet 72 having a front flange 74 which is at right angles thereto, which side in addition has a second right angle flange 76 which in turn terminates in an additional right angled flange 77, just as the opposite side is flanged. At the rear the side 72 is provided with a right angled flange 78. In addition there is the back 80, which is a plane, rectangular, longitudinally and vertically extending piece of sheet metal. This piece of metal lies in front of the two flanges 70 and 78 and is welded thereto as at 71 and 79, see Figure 6. At suitable places vertically spaced therealong the flange 60 at its junction with the side 58 is provided with a series of cut-outs 82 to receive hinge members 83. In a similar manner the front hollow post portion of the right side is provided with a series of spaced slots or cut-outs 84 likewise to receive the barrel portions of the hinges as hereinafter described. In addition, substantially midway of the length of the two front walls 60 and 74 of the posts just described, are provided the cut out slots 86 and 88 which, as shown in Figure 10, receive a rigidifying channel bar 90 having the two right angle parallel flanges 92 and 94 which extend into these slots and are welded thereto as at 95 and 98, see Figure 9. Rigidifying channel bars 100 each having parallel extending, right angularly disposed flanges 102 and 104, lie in the front corner post between the side 58 and the flange 62 and its terminal flange 64. There is another section of such an identically shaped channel 106 having the parallel flanges 108 and 110 which lie in this same location but directly below the cross bar 90, whereby the front bar 60, 62 and 64 is suitably rigidified. These vertical channel bars 100 and 106 are provided with spaced apart latch-receiving openings or slots 112, as hereinafter more fully described. In addition to the bars 100 and 106 there are similar bars 116 having the flanges 118 and 120 and the bar 122 having the flanges 124 and 126 which lie in the upper and lower portions of the front bars 74 and 76 above and below the rigidifying cross bar 90. These two bars 116 and 122 likewise have openings corresponding to the openings 112 of the correspondingly oppositely disposed bar to receive latch mechanisms therein.

The back 80 is provided with two vertical series of upwardly and downwardly facing struck out lips which provide oppositely extending supporting ledges 178 and 180, 178 being the downwardly extending lip and 180 being the upwardly extending lip, all as shown in Figures 7, 14 and 16, to receive the shelf edge and marginal walls of the hook rail assembly and the pot and pan supporting rail, and as shown in Figures 14, 23 and 27. These two vertical rows of lips are formed in the vertical edge portions of the back 80 at the points over which the flanges 70 on the sides 70 overlap so that the apertures or holes which are thus punched out are closed by these overlapping flanges from the rear.

There is also a top comprising the rectangular sheet 130 having the marginal skirts 132 and 134 likewise provided with an inwardly extending flange such as the flange 136 of the front skirt 132. This top member fits within the two sides

58 and 72 and the back 80 and its front corners fit within the slotted portions 138 of the post 60 and a corresponding cut out portion 139 of the upper portion of the post 74, and are welded or riveted thereto as at 140 and 142. These two sides 58 and 72 are welded as at 71 and 79 to the sides and to the back.

As shown clearly in Figure 13, one of the flanges such as 104 is provided with a free tongue portion 103 which is adapted to snap past the vertical edge of the flange 64 when the channel-shaped member 100 is inserted into position within this post formed by the sides 59, 60, 62 and 64. The channel member 106 is similarly provided with a free tongue to hold it in position.

Pairs of doors are provided for the front of the cabinet as shown in Figures 1 and 5 and 6. Each door is formed of a sheet metal piece 146, see Figure 5, provided with an upper flange 148 and curved arcuately at its bottom as at 150 and welded as at 152 to the edge of a rear facing of sheet metal 152 which has a flange 154 disposed between the weld 156 and the front 146. In addition, at its upper end the facing 152 is provided with a flange 158 which is welded as at 160 to flange 148. In addition, along the sides the front is provided with curved portions 162 and 164 which are welded to the inner portions of the vertically extending flanges 166 and 168 formed on the back portions 152 of each door. Overlapping flanges as shown at 170 and 172 are welded together at the vertical centers of the doors, as shown in Figure 6. At the central portion of the bar 30 rubber stops 174 are provided and rubber stops 176 are also provided at the lower edges of the doors. As hereinbefore stated, these doors are of identical construction and are therefore given similar reference numerals herein. Each door is preferably provided with a handhold 153. The upper doors may be opened separately from the lower doors.

The back 80 is provided with a spaced series of ledges therein formed in two vertical tiers. These ledges are spaced apart to provide downwardly extending lips 178 and correspondingly upwardly extending lips 180 and are spaced apart as shown, and extend preferably the full vertical length of the back wall of the cabinet. These members cooperate with the holes 112 in the front posts 100 and 106 on each side of the door 50 to receive fastening means for holding various attachments in position, and also to hold shelves in position.

Referring now to Figures 11, 12, 13 and 14, each shelf comprises a piece of sheet metal providing a top 184 having depending skirts 186 and 188, 190 and 192, at all four sides. At the front the depending skirt 186 is bent backwardly in diagonal fashion as at 187 and has its underside 191 welded as at 193 to the underside of the top 184. The diagonal portion 187 and the vertical front flange 186 are provided with registering holes to receive a locking member comprising a thimble 194 and a locking plunger 195 urged by a spring 196 forwardly out of the thimble 194. A gripping handle 200 is provided which may be pulled rearwardly to retract the latch 196 from the hole 112 in the front post 100.

The details of construction of this latching member are disclosed and claimed in my application Serial No. 562,419, filed November 8, 1944, and assigned to the common assignee of this present application.

At the rear the rear flange 192 of the shelf 184 is provided with an extension which is di-

agonally bent upwardly as at 202 and has an extension 204 welded as at 206 to the underside of the shelf top 184. In Figure 14 there is shown the manner in which the rear flange 192 of this shelf is held in position between the downwardly depending lip 178 and its spaced upstanding lip 180 on the back of the cabinet. Figure 2 of the drawings shows the cabinet as provided with the shelves in position.

In addition to, or in substitution for the shelves, the series of lips 178 and 180 on the rear wall 80 of the cabinet, and in conjunction with the holes 112 in the vertical posts 100 and 106, there is provided the rail assembly for hats and coats and other articles, shown particularly in Figures 21, 22, 23 and 24. As here shown, a U-shaped rail assembly is provided from three pieces or rails which have the general cross section shown in the end view at the left in Figure 22. Here there is provided a rail having a front vertical wall portion 208 which has two oppositely and parallel extending flanges 210 and 212. Flange 210 is provided with a right angular extending flange 214 and flange 212 is provided with an oppositely extending free flange 216. The ends of these flanged portions 214 and 210 and 212 and 216 are provided with ears or lugs 218 and 220 which extend transversely to the planes of the flanges 208, 214 and 216 and are preferably like the flanged portions 106 and 188 shown in Figure 12 to receive the latching device like that shown in Figure 12. The vertical wall 208 of this device may be provided with the spring clip mechanism 222 which may be riveted or welded thereto. The opposite end of this piece shown to the left in Figure 22 is angularly cut as shown at 224 and 226, 228, 230 and 232 to interfit with complementary end cut sections shown at 234, 236, 238, 240, 244, 246 and 248 of an additional rail 250 which is exactly the same shape in cross section as the rail 208. This rail at its opposite end is similarly configured as at the other end to interfit with a rail 252 which extends at right angles to the rail 250. The outer end of rail 252 is provided with tabs 254 and 256 which in turn are provided with the latching devices 258 and 260, like those shown at 196 on rail 208. Rail 250 may be provided with hooks 262 and 264 riveted or welded or otherwise fixed thereto. In Figure 23 the disposition of the hook rail assembly in the integral lips 178 and 180 at the back 80 of the cabinet is shown, together with the latches 196 entering the notches 112 in the front rails. The upper portions of the flanges 214 underlie the free ends of the downwardly extending lips 178 and the inside portions of the flanges 210 overlie the upwardly projecting lips 180 and underlie the downwardly projecting lips 178. The downward edges of the lips 216 lie behind the outwardly and upwardly projecting lips 180 whereby to hold the hook rail securely in position as shown in Figure 2.

In lieu of the hook rail, or in addition to the hook rail, a U-shaped hook rack may be provided as shown in Figures 25, 26, 27, 28 and 29. This hook rack is of the same general cross sectional configuration as the hook racks 208, 250 and 252. This hook rack is likewise formed of sections 266, 268 and 270 which at the junction of the separate sections are interfitted in the manner shown in Figure 29 and include end tabs 272 which interfit behind the front walls of the central section 268 in the manner therein shown. The front vertical central walls of these sections 266, 268

and 270 are provided with a series of holes 274 to receive the shanks 276 of hooks 278. The opposite ends of these shanks are carried by preferably rectangular blocks 280 which fit within the squared channel walls formed by the front surfaces 282 and the upper and lower surfaces 284 and 286 of this rail. When this rail, which is adapted to support pots and pans and other devices, is secured in place in the manner shown in Figure 27 by the lip members 178 and 180 of the back 80, the blocks will be held securely in position and the hooks rigidly held to receive the pots and pans and dustbrooms, and what not. The front portions of this rail are likewise provided with the right angularly disposed tabs 288 and 290 and latching devices 292 and 294, in the manner herein described, to cooperate with the holes 112 in the front posts 100 and 106.

In addition to the foregoing, there is provided a rack shown in Figures 15, 16 and 17 to hold the upper ends of certain of the shelves in vertically extending position whereby these shelves may be used as vertical dividers for the bottom of the cabinet so as to receive dustpans and other articles. The bracket is shown in Figure 17 as comprising two parallel straps 300 and 302, each of which has a front, upwardly extending, right angled portion 304 and 306 formed to hold one of the latching members 308 and 310 to engage the holes 112 in the front posts, hereinbefore described. In addition, the straps are provided with transversely extending slots 312 for purposes hereinafter described. Each strap is provided with a reversely bent, oppositely extending flange 314 to which is welded a cross strap 316 which unites the two straps 300 and 302 and gives it rigidity. When in position these straps 300 and 302 are held by the upper and lower lips 178 and 180 of the back 80 and are likewise held by the latch mechanisms 308 and 310 engaging the holes 112 in the front posts.

Two of the shelf members shown in Figure 11 are now utilized to form in conjunction with a bottom support a series of vertical dividers. The bottom support is shown in Figure 19 as comprising a sheet metal plate-like member 318 to which is affixed a linoleum plate 322. Riveted thereto as at 324 are a series of U-shaped clips 326 and 328 and L-shaped clips 330 and 332 so that when this linoleum bottom plate is placed in position and rests upon the bottom 40 of the cabinet, it will provide the clip-like spacers for receiving the rear flanged ends 192 of the shelves, the latching mechanisms of the front walls 186 of these shelves entering the openings 312 of the strap 300 and 320 whereby securely to hold these shelf dividers in position as shown in Figures 4 and 16.

By referring to Figures 1 to 4 inclusive it will be seen that the cabinet as herein constructed, together with the auxiliary devices and attachments, provides a wardrobe or cabinet having a plurality of uses. For instance, in Figure 2 the shelves 186 are inserted at the top in the manner hereinbefore described, and the coat rack shown at 250 in Figure 21 is preferably inserted in the position indicated, although it may occupy a higher or a lower vertical position with respect to the cabinet. The bottom portion of the cabinet in Figure 2 is not provided with shelves for the storage of articles.

In Figure 3 the wardrobe is shown as being provided with a vertical tier of the shelves, and in Figure 4 the cabinet is shown as provided with a series of pan support rails and with two of the

shelves disposed vertically with the linoleum bottom in position to hold the bottom of the shelves, the clip rack shown in Figure 17 holding the top portions of the shelves as shown in Figure 16. The adaptability of the cabinet to these various changes is secured by providing the two vertical series of tongue-like lips 178 and 180 shown in Figures 14 and 23, in cooperation with the latch members 196 and the perforations 112 in the two front posts 100 and 106. These lips and holes cooperate with the coat rail assembly and the pot and pan rails to provide various combinations of compartments, rails, and shelves herein illustrated.

Obviously the invention is not limited to the specific details of construction disclosed herein but is capable of other modifications and changes without departing from the spirit and scope of the appended claims.

Having thus described my invention, what I claim as new and desire to secure by Letters Patent is:

1. A cabinet having two spaced sides and a back formed of sheet metal, the back being formed with two spaced vertical series of integral struck out lips spaced apart vertically, alternate lips extending upwardly and inwardly, and alternate lips extending downwardly and inwardly, a support rail comprising two parallel legs and a back, said rail having a cross section providing an intermediate vertical wall and upper and lower horizontal parallel flanges each terminating in upwardly and downwardly disposed vertical terminal flanges lying in a common plane, the upper edge of one of said last mentioned flanges underlying a downwardly extending lip and the lower edge of the lowermost of said last mentioned flanges overlying an upwardly extending lip, the free ends of the parallel leg portions of said rail being provided with shiftable latch mechanisms adapted to engage a front wall of the cabinet whereby to cooperate with the upwardly and downwardly extending lips on the back wall of the cabinet for holding the support rail on the cabinet, the vertical central portion of said rail being provided with openings and means having a portion passing through an opening in said central portion of said rail and projecting forwardly thereof into the interior of the cabinet for holding an article.

2. A cabinet having two spaced sides and a back formed of sheet metal, the back being formed with two spaced vertical series of integral struck out lips spaced apart vertically, alternate lips extending upwardly and inwardly, and alternate lips extending downwardly and inwardly, a pot and pan support rail comprising two parallel legs and a back and having a cross section provided with an intermediate vertical wall and upper and lower horizontal parallel flanges each terminating in upwardly and downwardly disposed terminal flanges lying in a common plane, the upper edge of one of said last mentioned flanges underlying a downwardly extending lip and the lower edge of the lowermost of said last mentioned flanges overlying an upwardly extending lip, the free ends of the leg portions of said rail being provided with shiftable latch mechanisms adapted to engage a front wall of the cabinet whereby to cooperate with the upwardly and downwardly extending lips on the back wall of the cabinet for holding the support rail on the cabinet, the vertical central portion of said rail having article holding means thereon projecting into the interior of the cabinet.

net, said rail having detachable interlocking joints between the back and the two leg portions.

3. A cabinet comprising two sides and a back, the sides terminating in vertically extending, spaced apart front posts providing an opening therebetween, channel members vertically received in said posts, the inner vertical walls of said posts being provided with a series of vertically spaced openings, the back member in registration with said front openings being provided with a vertical series of spaced apart, integral, inwardly struck lips providing spaced apart horizontal supports, said cabinets having a bottom, a plate-like member adapted to rest on said bottom and having spaced pairs of upstanding clips, a strap-like support comprising two horizontal straps and an interconnecting strap at the rear, the front edges of said straps having upstanding vertical flange portions, a spring pressed latch carried by each of said flange portions, the horizontal straps being provided with spaced slots therein, the cross strap being bent at right angles to the two spaced straps, and a partition of sheet metal having right angled skirts integrally formed therewith, the front and back skirts having extensions bent diagonally upwardly and underlying and secured to the underside of the body of the partition, a spring pressed latch mechanism mounted in the front skirt at spaced points thereof, and including a forwardly projecting plunger, said partition being vertically positioned in said cabinet with its rear skirt lying in a pair of the clips on the bottom plate and with the spring pressed latch members projecting outwardly and engaging in the slots of the spaced straps of the bracket members whereby to hold said partition in vertical position at the bottom of the cabinet, the transversely disposed cross strap at the rear interconnecting said two spaced straps having its lower edges overlying one of the upwardly extending lips, the top edge of the cross strap underlying one of the downwardly depending lips on the back of said cabinet.

4. A sheet metal rail assembly comprising a back portion and two leg portions, the ends of said back and leg portions having angularly disposed slots therein arranged to interfit so as to maintain the back and legs at right angles to each other, the cross section of the back and the two legs including a vertical intermediate wall portion and upper and lower parallel longitudinally extending flanges, the two flanges terminating in oppositely extending vertical flanges lying in a common plane, and article supporting means carried by the vertical intermediate portion, the outer ends of said leg portions including upper and lower lugs extending at right angles to the plane of said intermediate vertical wall, and latch mechanisms carried thereby and extending outwardly at right angles to the plane of the lugs.

5. A cabinet having two spaced sides and a back formed of sheet metal, the back being formed with two vertically disposed spaced series of integrally struck out lips spaced apart vertically, alternate lips extending upwardly and inwardly, and alternate lips extending downwardly and inwardly, and a rail assembly comprising two spaced apart parallel legs and a transversely disposed back portion disposed normally to and connected at its ends to have legs, the back portion of said rail assembly having vertically spaced horizontal flange portions extending inwardly of the rear edge thereof and oppositely directed vertical flanges at the rear edges of said horizontal

flange portions, said rail assembly being mounted in the cabinet in such a manner that the upwardly and downwardly extending adjacent lips of the back of the cabinet underlie and overlie certain of the surfaces of said horizontal flange portions of the rail, and that the next adjacent lips below and above said first mentioned pair of lips underlie and overlie the bottom and top edges of the vertical flanges of said horizontal portions, and means for detachably securing the front edges of said two sides of said rail assembly to the front of the cabinet.

6. A cabinet including a back and two vertically extending spaced sides, each side at the front being bent reversely inwardly to form an integral hollow substantially rectangular column, the inner free end of said reversely bent portion being spaced from the adjacent side wall, a rigidifying channel of sheet metal having an intermediate wall and integral spaced parallel side flanges, said channel being disposed in the space between the adjacent side wall and the free inner end of said reversely bent portion, and the flange of said channel adjacent said free inner end of the rectangular column having a tongue portion formed thereon adapted to engage said free end whereby to hold said channel in assembled relationship with said column.

7. A cabinet including a back and two vertically extending spaced sides, each side at the front being bent reversely inwardly to form an integral hollow substantially rectangular column, the inner free end of said reversely bent portion being spaced from the adjacent side wall, a rigidifying channel of sheet metal having an intermediate wall and integral spaced parallel side flanges, said channel being disposed in the space between the adjacent side wall and the free inner end of said reversely bent portion, the flange of said channel adjacent said free inner end of the rectangular column having a tongue portion formed thereon adapted to engage said free end whereby to hold said channel in assembled relationship with said column, and means formed on said back and said channels adapted to support auxiliary article supporting portions.

8. A cabinet including a back and two vertically extending spaced sides, said back having two spaced vertical series of integral struck out lips spaced apart vertically, certain of said lips in each series extending upwardly and inwardly and alternate lips in each series extending downwardly and inwardly, each side at the front being bent reversely inwardly to form an integral hollow substantially rectangular column, the inner end of said reversely bent portion being spaced from the adjacent side wall, a rigidifying channel of sheet metal having an intermediate wall and integral spaced parallel side flanges, said channel being disposed in the space between the side wall and the free inner end of said reversely bent portion, the flange of said channel adjacent said free inner end of the rectangular column having a tongue portion formed thereon adapted to engage said free end whereby to hold said channel in assembled relationship with said column, and the intermediate wall of said channel having a vertical series of apertures formed therein, said lips and said apertures being adapted to co-operate to support auxiliary supporting means.

9. A cabinet as set forth in claim 8, wherein the inwardly extending portions of the lips are arcuate in a direction vertically of the back and

the curved free edges of each of the lips lie in a plane substantially perpendicular to the back.

10. A cabinet including a back and two vertically extending spaced sides, said back having two spaced vertical series of integral struck out lips spaced apart vertically, certain of said lips in each series extending upwardly and inwardly alternate lips in each series extending downwardly and inwardly, each of said sides having a flange overlying the rear wall of the back and overlying the openings formed by said lips to close said openings, each side at the front being bent reversely inwardly to form an integral hollow substantially rectangular column, the inner end of said reversely bent portion being spaced from the adjacent side wall, a rigidifying channel of sheet metal having an intermediate wall and integral spaced parallel side flanges, said channel being disposed in the space between the side wall and the free inner end of said reversely bent portion, the flange of said channel adjacent said free inner end of the rectangular column having a tongue portion formed thereon adapted to engage said free end whereby to hold said channel in assembled relationship with said column, and the intermediate wall of said channel having a vertical series of apertures formed therein, said lips and said apertures being adapted to co-operate to support auxiliary supporting means.

HARVEY G. KNUTH. 30
